UNITED STATES PATENT OFFICE.

FREDERICK WILLIAM GRELL, OF NEW YORK, N. Y., ASSIGNOR TO THE AMERICAN HARD RUBBER COMPANY, OF SAME PLACE.

DESIGN FOR A COMB.

SPECIFICATION forming part of Design No. 33,537, dated November 13, 1900.

Application filed October 16, 1900. Serial No. 33,297. Term of patent 14 years.

To all whom it may concern:

Be it known that I, FREDERICK WILLIAM GRELL, a citizen of the United States, residing at New York, (College Point,) county of 5 Queens, and State of New York, have invented and produced a new and original Design for Combs, of which the following is a specification.

My design consists, essentially, of a comb 10 the back of which at its sides is protuberant and ribbed.

In the accompanying drawings, Figure 1 is 15 a side elevation of a comb embodying my design. Fig. 2 is a cross-sectional view of a comb embodying my design and drawn to a larger scale than Fig. 1.

Similar letters of reference designate corresponding parts in both of the figures.

A represents the back of a comb, and B the 20 teeth of the comb. The back at the lower

portion of its sides is protuberant, as shown at a. The edges of the teeth B are extended upward and form ribs a², which project from the protuberant portions a. The spaces a¹ between the ribs are rounded transversely. 25

The leading or essential feature of my design is the ribbed and protuberant portion on each side of the comb-back.

Having thus described my invention, what I claim as new, and desire to secure by Letters 30 Patent, is—

The design for a comb substantially as herein shown and described.

In testimony whereof I have signed my name to this specification in the presence of 35 two subscribing witnesses.

FREDERICK WILLIAM GRELL.
